US0D1053873S

(12) **United States Design Patent** (10) Patent No.: **US D1,053,873 S**
(45) Date of Patent: ** Dec. 10, 2024

(54) **AUDIO VISUAL PERIPHERAL EQUIPMENT**

(71) Applicant: **Lenovo (Beijing) Limited**, Beijing (CN)

(72) Inventor: **Qian Qian**, Beijing (CN)

(73) Assignee: **Lenovo (Beijing) Limited**, Beijing (CN)

(**) Term: **15 Years**

(21) Appl. No.: **35/518,658**

(22) Filed: **Jun. 13, 2023**

(80) **Hague Agreement Data**

Int. Filing Date: **Jun. 13, 2023**

Int. Reg. No.: **DM/232004**

Int. Reg. Date: **Jun. 13, 2023**

Int. Reg. Pub. Date: **Oct. 13, 2023**

(30) **Foreign Application Priority Data**

Dec. 13, 2022 (CN) 202230834288.8

(51) **LOC (14) Cl.** **14-01**

(52) **U.S. Cl.**

USPC **D14/388; D14/125**

(58) **Field of Classification Search**

USPC D14/125, 126, 129, 133, 496, 167, 204, D14/217, 221, 225, 226, 238.1, 239, 356, D14/432, 511, 388, 218; D16/202, 208, D16/203, 211, 229; D21/333; D10/70, D10/106.6, 106.7

CPC .. H05K 5/00; H05K 5/03; H04N 7/15; H04N 5/64; H04M 3/567; G03B 17/02

(57) **CLAIM**

The ornamental design for an audio visual peripheral equipment as shown and described.

DESCRIPTION

1.1: Front

1.2: Back

1.3: Left

1.4: Right

1.5: Top

1.6: Bottom

1.7: Top perspective view

1.8: Bottom perspective view

1.9: Perspective view in an alternative state

The broken lines shown in the drawings illustrate portions of the audio visual peripheral equipment that form no part of the claimed design.

The dot-dash broken lines illustrate the boundary of the claimed design and form no part thereof.

1 Claim, 9 Drawing Sheets
